UNITED STATES PATENT OFFICE

2,326,473

PETROLEUM HEATER

Roy S. Lyster, Lansdowne, Pa., assignor to Alcorn Combustion Company, Philadelphia, Pa., a corporation of Delaware

Application September 22, 1941, Serial No. 411,891

2 Claims. (Cl. 122—356)

My invention relates to heating systems, more particularly to petroleum heaters of the type used to heat petroleum or its derivatives to distillation temperatures or to higher temperatures to produce chemical changes therein such as by cracking, thermally or catalytically, by polymerization, or otherwise, and has for an object the provision of a reliable heater having great flexibility in the control of the application of heat to the petroleum.

For a complete understanding of my invention reference should be had to the drawing wherein:

Fig. 1 is a sectional elevation of a heater embodying my invention; and

Fig. 2 is a sectional view taken on the line 2—2 of Fig. 1.

In the form of my invention shown on the drawing, the heater includes fire chambers 10, 11, and 12, the chambers 10 and 12 being in end to end or back to back relation with respect to each other and separated from each other by fire chamber 11. Suitable fuel such as oil or gas is by a plurality of burners 14 introduced into associated muffles 15 wherein partial combustion of the fuel occurs. The still-burning gases are by the muffles 15 directed horizontally across the fire chamber 10 towards the rear wall 16. The several streams of gases after passage over and above a large portion of a bank of floor tubes 17 rise upwardly into convection section 18.

From a front or side wall 19 of the heater a roof portion 20 slopes upwardly so that a bank of roof tubes 21 which also slopes upwardly is to a large degree disposed without the path of the streams of still burning gases.

The sloping roof 20 terminates in a more abruptly or steeply sloping section 22 which joins with a horizontal section 23 from which rises one wall 24 of a central convection section 25. A floor 27 is common to the fire chambers 10, 11 and 12.

The fire chamber 12 in the illustrated form of my invention is an exact duplicate of the fire chamber 10 and the same reference numerals have been applied to like parts together with the subscript "a". The foregoing description is equally applicable thereto and will not be repeated.

The rear walls 16 and 16a of fire chambers 10 and 12 form bridge walls and boundary walls for the intermediate or central fire chamber 11 into which still burning gases are directed by burners 28 over and above floor tubes 29. The burners 28 and associated muffles are located at the end

walls 30 and 31 of the heater and direct the gases and combustion products longitudinally above the floor tubes 29 which are below and without the paths of the combustion gases. The rear walls 16 and 16a also form bridge walls over the tops of which pass convection gases and their upper portions in conjunction with the inclined roof portions 22 and 22a define convection sections 18 and 18a.

10 Many advantageous results are secured as a result of the illustrated embodiment of my invention. Thus three separately controlled radiant chambers and three convection sections are provided in a space normally used for two radiant fire chambers and one convection section.

The heater may be used for the heating of a very large volume of oil or petroleum per hour by suitable parallel connection of the several banks of tubes. For example, the tubes in the central convection section may be connected by headers (not shown) for flow of two streams therethrough, one passing through convection section 18a, roof tubes 21a and floor tubes 17a; and the other stream passing through convection section 18, roof tubes 21 and floor tubes 17. The two streams may then discharge into a flash drum (not shown) and vapors withdrawn therefrom may be superheated in floor tubes 29 connected in series or in parallel.

30 Where the treatment of the oil or petroleum requires exact control of the application of heat my invention is particularly useful. For example, as shown by the broken lines between the inlet and outlet, headers (not shown) may connect the tubes for passage of the charge serially through the tubes of the central convection 25 for the initial heating of the charge. Overheating in section 25 is effectively avoided even though it is exposed to the radiant heat of fire chamber 11.

35 Each convection section 18 and 18a lowers the temperature of the convection gases passing therethrough and these gases of relatively low temperature join with the gases from the central fire chamber 11. Both streams of convection gases serve to moderate or lower the temperature of the gases from chamber 11 and application of heat to the tubes in section 25 at excessively high rate is avoided. However, a relatively efficient transfer of heat is maintained in section 25 by reason of the large volume of gases passing therethrough, that is, all the gases from chambers 10, 11, and 12.

40 After its initial heating, the stream of oil may 50 then pass through convection sections 18a and

18, thence through roof tubes 21, floor tubes 11, 29, and 11a, and after passage through roof tubes 21a it may be subjected to desired treatment in the refinery. In chamber 10, the rate of heat application may be relatively moderate, in chamber 11 at high rate, and in chamber 12, either the high rate may be continued or moderate "soaking" heat may be applied.

A heater of the type embodying my invention is of relatively low cost considering its great flexibility. The structural steel for supporting the tubes, the tube sheets, and walls is no more complicated than for a typical double-end fired heater as shown in Nash et al. Patent No. 2,229,253 and yet two additional heating sections have been added. The triple function of walls 16 and 16a does not impose upon them excessive demands which would tend to shorten their life. By varying the length of the tubes, the number of burners, and by selecting a sequence of oil flow to meet the heating requirements, a wide variety of heating needs may be adequately and satisfactorily met.

In the foregoing description and in certain of the claims reference is made to fire chambers 10 and 12 as end to end or back to back. The walls 19 and 19a may be considered the front walls and the walls 16 and 16a the rear walls of the fire chambers 10 and 12. The walls 30 and 31 would then be considered as the end walls of fire chamber 10 and the fire chambers 10 and 12 would then be considered as back to back. It is also true the rear end or wall 16 is adjacent or next to rear or end wall 16a and therefore the heaters are "end to end," which latter term is to be read to cover and to define the structure shown and its equivalents.

What I claim is:

1. A heater having a floor, a roof, and walls defining a pair of fire chambers disposed end to end on opposite sides of a centrally located fire chamber, the rear walls of said pair of fire chambers terminating short of said roof, an intermediate convection section, spaced above said rear walls and directly over said intermediate fire chamber, said roof sloping upwardly from opposite side walls of the heater and terminating at said central convection section, a

plurality of tubes horizontally disposed between the roof and the upper portion of each of said rear walls to form individual convection sections for said pair of fire chambers, a bank of roof tubes and a bank of floor tubes horizontally disposed adjacent the roof and floor of said pair of fire chambers and means disposed intermediate said roof and floor tubes for burning fuel in a plurality of streams within said pair of chambers, fuel burning means located at the opposite end walls of said intermediate fire chamber, a bank of floor tubes in said intermediate fire chamber horizontally disposed materially below said last-named means, and means for connecting said tubes for passage of oil therethrough.

2. A heater having a floor, a roof and walls defining a pair of fire chambers disposed end to end and each including heat-refractory rear walls spaced one from the other to define between them an intermediate fire chamber, each of said rear walls terminating short of the roof of the heater, a central convection section disposed directly above said intermediate fire chamber and in communication with each of said fire chambers, a plurality of horizontal tubes disposed adjacent the upper ends of each of said rear walls and forming convection sections individual to said pair of fire chambers, banks of radiant fluid-conducting heat-absorbing tubes in each of the pair of fire chambers horizontally disposed along the floor and roof thereof, a plurality of burners for each one of the pair of fire chambers located between said roof and floor tube banks, the gases and products of combustion from said burners passing across each said chamber and through said convection sections individual thereto, a bank of horizontal tubes disposed adjacent the floor of said intermediate fire chamber, burners for introducing burning gases in a plurality of streams above said last-mentioned floor tubes and in direct view of said central convection section, the gases from each of the pair of fire chambers passing over said rear walls and in mixture with the gases from said intermediate fire chamber passing through said central convection section.

ROY S. LYSTER.
